Primary Examiner—Robert M Spear*Assistant Examiner*—Susan E Krakower(74) *Attorney, Agent, or Firm*—Gottlieb, Rackman & Reisman(57) **CLAIM**

The ornamental design for a jewelry element, as shown and described.

DESCRIPTION

FIG. 1 is a front elevational view showing my new design:

FIG. 2 is a right side elevational view thereof;

FIG. 3 is a top plan view thereof;

FIG. 4 is a left side elevational view thereof;

FIG. 5 is a rear elevational view thereof; and,

FIG. 6 is a bottom plan view thereof.

The broken lines in the drawing form no part of the claimed design and indicate that the entire top surface and the gem stone of the jewelry element are unclaimed.
